UNITED STATES PATENT OFFICE.

GEORGE T. McELROY, OF MABEN, WEST VIRGINIA.

IMPLEMENT FOR BENDING OR STRAIGHTENING RAILS.

1,139,878.

Specification of Letters Patent. Patented May 18, 1915.

Application filed April 4, 1914. Serial No. 829,653.

To all whom it may concern:

Be it known that I, GEORGE T. McELROY, citizen of the United States, residing at Maben, in the county of Wyoming and State 5 of West Virginia, have invented certain new and useful Improvements in Implements for: Bending or Straightening Rails, of which the following is a specification.

My invention has reference to an improved implement for either bending or straightening railway rails.

As its primary object the invention contemplates a construction wherein and whereby means is provided for firmly grasping 15 the rail acted upon at points in spaced relation and subsequently exerting an even steady pressure thereupon intermediate said points to in this manner either bend or straighten that portion of the rail therebetween.

The invention as a further object aims to provide an operating screw having a nut associated therewith, the latter being so arranged relatively to the implement proper 25 as to provide for longitudinal movement, when in use, of the screw in either direction, said movement being effected through a turning of the nut.

The above and additional objects are accomplished by such means as are illustrated 30 in their preferred embodiment in the accompanying drawings, described in the following specification and then more particularly pointed out in the claims which are 35 appended hereto and form a part of this application.

In describing my invention in detail reference will be had to the accompanying drawings wherein like characters denote like 40 or corresponding parts throughout the several views, and in which:—

Figure 1 is a side elevation illustrating the manner in which a railway rail may be straightened; Fig. 2 is a section on the 45 line 2—2 of Fig. 1; Fig. 3 is a side elevation illustrating a different application of the invention to an ordinary railway rail; Fig. 4 is a section on the line 4—4 of Fig. 3; and Fig. 5 is a section on the line 5—5 of Fig. 3.

Before proceeding with the description of the drawings, I desire to call particular attention to the fact that while I have evolved my invention with reference to its applica-

tion in connection with railway rails, the same may be readily utilized as a means for 55 straightening or bending metal bars, pipes or the like.

Referring now to the drawings by numerals, 1 designates the body portion of the implement, the said body portion being substantially U-shaped and provided with an opening 2 extending longitudinally of the connecting portion thereof. A second opening 3 extends transversely of the opening 2 and of the connecting portion of the 60 said body, said opening 3 being positioned to receive an operating screw 4 extending longitudinally of the device. A nut 5 fits the opening 2, said nut being threaded upon the screw 4 and locked against longitudinal 65 movement upon a turning thereof by reason of its engagement with the respective walls of the said opening, such arrangement causing the screw 4 to move longitudinally relatively to the body portion 1. Said screw 4 70 is enlarged at one end as indicated at 6, the enlargement being cut away as at 7 to provide for the arrangement of the said enlargement over the railway rail to be bent or straightened. Openings 8, aligned, and 75 formed, one within each of the extensions of the said enlargement 6 are adapted to receive a pin or keeper 9, which, in the practical application of the invention is adapted for engagement with the under surface of the base 80 flange of the rail.

The respective terminals of the extensions of the body portion 1 are slightly concaved to engage the tread of the rail (in the use 85 of the implement as illustrated in Figs. 1 90 and 2 of the drawings) to support the rail immovable in the operation necessary to the straightening of a bend or depression therein.

In the use of the device in the manner 95 illustrated in Figs. 3 to 5 inclusive, the rail acted upon is not fitted within the cut out portion 7 of the enlargement 6, but is so positioned relatively to said enlargement as to cause the tread portion of the rail to fit 100 or engage a groove 10 extending transversely of the cut out portion 7, one edge or corner of the enlargement being in engagement with the base flange of the rail, this arrangement causing an even pressure 105 to be exerted upon one side of the rail in a

straightening operation. Retaining elements 11, substantially hook-shaped, are provided, one being detachably secured to each extension of the body 1 as illustrated to advantage in Fig. 3 of the drawings. Said elements 11 are provided with openings 12 for the reception of pins or projections 13 of the body, this arrangement causing the elements to be held rigid or against longitudinal movement and in this manner to support the rail in the desired relation upon the turning of the nut 5 and the application of pressure in a straightening operation.

In a bending operation, the retaining elements 11 are arranged over the pins or projections 13 in the manner illustrated in Fig. 3, said elements being disposed to overlap the rails, in which position, a turning of the nut 5 in one direction will cause the enlargement 6 to engage the tread portion of the rail and, as the latter is held immovable with respect to the body, continued turning of the nut 5 will cause the screw to bend the rail in the desired manner.

From the foregoing, taken in connection with the accompanying drawings it is apparent that either a bending or straightening of the rails may be effected by a reverse turning of the operating screw 4; that the keeper 9 serves as an abutment for the rail in straightening same in one application of the device, while the retaining elements 11 serve as an abutment for the rail in straightening the same in the other application of the device; and that by the provision of the groove 10 in the enlargement 6 of the screw, an even pressure is exerted upon the rail, both at the base flange and at the tread flange thereof.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

1. In a device of the character described, a body portion engageable with the article acted upon, an operating element movable relatively to said body, the said element having alined openings formed therein, detachable means secured to said body and engageable with the article acted upon, said means maintaining the article in engagement with said body, the said screw being further provided with intersecting transverse grooves, one of the said grooves being adapted to receive the article acted upon when bending said article vertically and the other of the said grooves being shaped to receive the said article when bending the article laterally, and a removable element fitting the alined opening aforesaid to maintain the said article within one of the said grooves when bending the said article vertically, as and for the purpose set forth. 75

2. In a device of the character described, a body portion engageable with the article acted upon, an operating element movable relatively to said body, pins projecting laterally from said body, detachable means secured to the pin and engageable with the article acted upon, said means maintaining the article in engagement with said body, a head formed upon said operating screw, the said head having alined openings formed therein, the said head being further provided with intersecting transverse grooves, one of the said grooves being shaped to receive the article acted upon when bending the said article vertically and the other of the said grooves being shaped to receive the said article when bending the article laterally, and a removable element fitting the opening aforesaid to maintain the said article within one of the said grooves when bending the said article vertically, as and for the purpose set forth. 80 85 90 95

In testimony whereof I affix my signature in presence of two witnesses.

GEORGE T. McELROY.
